Application January 28, 1938, Serial No. 74,619

Term of patent 7 years

To all whom it may concern:

Be it known that I, Wallace H. Benton, a citizen of the United States, residing at Portsmouth, in the county of Scioto and State of Ohio, have invented a new, original, and ornamental Design for a Shoe, of which the following is a specification, reference being had to the accompanying drawing, forming a part thereof.

Figure 1 of the drawing is a side elevation of a shoe, showing my new design.

Figure 2 of the drawing is a perspective view of a shoe, showing my new design.

Figure 3 is a fragmentary top plan view of the toe portion of the shoe. A particular feature of my design is the colored beading between the upper and sole portions of the shoe harmonizing with the trim in the manner illustrated.

I claim:

The ornamental design for a shoe, substantially as shown and described.
